(57) CLAIM

The ornamental design for a card wallet, as shown and described.

DESCRIPTION

FIG. 1 is a front, right, bottom perspective view of a card wallet, embodying my new design;

FIG. 2 is a rear, left, bottom perspective view thereof;

FIG. 3 is a front view thereof with an inserted card;

FIG. 4 is a rear view thereof with an inserted card;

FIG. 5 is a front view of FIG. 1;

FIG. 6 is a left side view thereof;

FIG. 7 is a right side view thereof;

FIG. 8 is a top plan view thereof;

FIG. 9 is a bottom plan view thereof;

FIG. 10 is a rear view thereof; and,

FIG. 11 is a cross-section view taken along line 11-11 of FIG. 10.

The broken lines are provided for purposes of illustration and form no part of the claimed design.
